UNITED STATES PATENT OFFICE

117,351

DESIGN FOR A CONDIMENT SHAKER

Thomas J. Elia, Chicago, Ill.

Application August 29, 1938, Serial No. 79,620

Term of patent 3½ years

To all whom it may concern:

Be it known that I, Thomas J. Elia, a citizen of the United States, residing at Chicago, in the county of Cook and State of Illinois, have invented a new, original, and ornamental Design for a Condiment Shaker, of which the following is a specification, reference being had to the accompanying drawing, forming a part thereof.

Fig. 1 is a side elevational view of a condiment shaker, the stippled area representing a color different from the remaining areas.

Fig. 2 is a top plan view thereof.

The characterizing feature of the design resides in the condiment shaker of the configuration shown having a knurled portion which is rounded over the top portion of the shoulder of the cap member thereof, said knurled portion flowing in with the external configuration of the design, providing a continuous unbroken profile, as shown.

I claim:

The ornamental design for a condiment shaker, substantially as shown and described.

THOMAS J. ELIA.
